UNITED STATES PATENT OFFICE.

FRED MATHEWS, OF CHICAGO, ILLINOIS, ASSIGNOR TO CLINTON C. MURPHY, OF CHICAGO, ILLINOIS.

CAR-DOOR.

1,185,818.

Specification of Letters Patent.

Patented June 6, 1916.

Application filed May 24, 1913. Serial No. 769,634.

To all whom it may concern:

Be it known that I, FRED MATHEWS, a citizen of the United States, residing at Chicago, in the county of Cook and State of Illinois, have invented certain new and useful Improvements in Car-Doors, of which the following is a specification.

My invention relates to car doors of the type shown in my copending application, 10 Serial No. 756,425, filed March 24th, 1913, in which the door is supported on rollers arranged under the lower edge thereof.

The invention has for its object to provide certain improved arrangements relating to the means employed for retaining and guiding the upper edge of a door of this type.

I have shown in the drawings annexed hereto and will describe herein several alternative constructions, each of which has for its purpose to provide simple and inexpensive means for holding the upper edge of a door in place, guiding it during the opening and closing movements of the door and preventing dust, cinders, sparks, rain, snow and the like from being driven into the car over the top of the door. These constructions are designed, furthermore so that the elements thereof reinforce, stiffen and strengthen the door and the door frame, and, so far as certain of said constructions are concerned, so as to provide means for supporting the door and preventing it from falling from the car in case the rollers 35 which normally support it should be injured, broken off or detached.

With reference to the drawings: Figure 1 is a fragmentary side elevation of a railway box car showing the door thereof provided with retaining guiding means constructed in accordance with my invention; Fig. 2 is a sectional view on line 2—2 of Fig. 1; Figs. 3 and 4, a fragmentary sectional view and elevation illustrating a modified construction; and Figs. 5, 6 and 7, fragmentary sectional views showing three other modified constructions.

Like characters of reference designate like parts in the several figures of the drawings.

In the drawings, 10 designates the side sheathing of a car, 11 the side plate, 12 the side sill, 13 the door opening and 14 a sliding door. The latter is supported upon 55 rollers 15 which are preferably mounted in

retaining brackets 16 having lips 17 which project above the lower edge of the door, the latter being preferably provided with the angular wear strip 18.

Referring particularly to Figs. 1 and 2, 60 a guide strip 19 is secured by means of bolts 20, or other suitable means, to a fascia block 21 above the door opening. The upper edge of the door is provided with a guide strip 22 having a U-shaped flange or 65 lip 23 extending around an inturned flange 24 formed on the guide strip 19. The horizontal portion 25 of the U-shaped flange 23 is not intended under normal conditions to come into contact with the flange 24. However, if the supporting devices at the lower edge of the door should be accidentally broken off or detached, the engagement between the guide strips at the upper edge of the door will prevent the door from falling 70 from the car. In fact, under these conditions the door may be moved back and forth to open and close it, although not so easily as when supported, as intended, upon the rollers 15. Under all conditions the strips 19 and 22, together with the door frame member 26, serve to retain the upper edge of the door in proper position and guide it during the opening and closing movements of the door. The 75 strips reinforce, strengthen and stiffen the door and also the door frame. Being angular in cross-section, they are well calculated to perform this function. Furthermore, their relationship is such as to provide effective means for preventing rain, 80 snow, dust, cinders and the like from blowing into the car over the top of the door.

In the arrangement shown in Figs. 3 and 4 the guide strip on the car is an L-section 95 strip 27, the vertical flange of which is fitted into a kerf in the fascia block 28. This arrangement gives additional security against the entrance of water into the car. The guide strip on the door, the latter designated 29, consists of a Z-bar 30, the upper flange of which 31 extends back of the guide strip 27. On the front of the door are secured angular clips 32, the horizontal flanges 33 of which extend over, preferably without touching, the horizontal flange 34 of the guide strip 27. These devices support the door on the guide strip 27 in case of accident to the supporting elements at the lower edge of the door and, furthermore, limit the in- 100 105 110

ward movement of the upper edge of the door so that dependence does not have to be placed in this regard upon the door frame member 26. It will be seen that if rain is driven into the space between the top of the door and the flange 34 of the guide strip 27, it is intercepted and prevented from entering the car by the vertical flange 31 of the guide strip 30.

10 The arrangement in Fig. 5 is the same as that in Figs. 3 and 4 except that the guide strip 27, instead of being secured in a kerf in the fascia block, here designated 35, is fastened against the outer face of the same.

15 In Fig. 6 the guide strip on the car consists of a Z-bar 36. The construction is otherwise the same as in Fig. 5. The depending lip or lower vertical flange 37 of the Z-bar 36, by projecting down in front of 20 the Z-bar 30 on the door, makes this construction more certainly water-proof than that shown in Fig. 5.

Fig. 7 shows an extremely simple construction in which the guide strip on the car 25 consists of a flat bar or strip 38, the guide strip on the door consisting of a Z-bar 30 as in the three constructions last described. The upper vertical flange 31 of the Z-bar 30 extends between the strip 38 and the upper 30 door frame member 26 so as to retain the upper edge of the door in position and guide it when the door is opened and closed. This arrangement also gives some measure of protection against the danger of water and 35 the like being blown into the car over the top of the door.

While I have described my invention in certain preferred embodiments, it will be understood that modifications might be 40 made without departing from the principles of the invention.

I claim:

1. The combination with a railway car provided with a door normally supported along its lower edge only and beyond the 45 outer edge of the door opening, of a guide strip formed with a lateral projection on the car above the door opening, and a guide

strip on the door having a flange which projects upwardly from the door back of said 50 first-named strip, the said guide strip on the door being formed with a lateral flange which overhangs said projection on the first-named guide strip, for the purpose described.

2. The combination with a railway car provided with a door normally supported along its lower edge only and beyond the outer edge of the door opening, of a guide strip formed with a laterally extending 60 flange on the car above the door opening, and an angular guide strip secured to the upper edge of the door having a flange which projects upwardly from the door back of said first-named guide strip, said angular 65 guide strip being formed with means which overhang said laterally extending flange on said first-named guide strip for the purpose described.

3. The combination with a railway car 70 provided with a door normally supported along its lower edge only and beyond the outer edge of the door opening, of a guide strip on the car above the door opening, and an angular guide strip on the door having a 75 flange which covers the upper edge of the door and an upwardly projecting flange which extends back of said first-named guide strip, said upwardly projecting flange being provided with means which overhang said 80 first-named guide strip for the purpose described.

4. The combination with a railway car provided with a door normally supported along its lower edge only and beyond the 85 outer edge of the door opening, of a guide strip on the car above the door opening formed with an inturned flange, and a guide strip on the door having a substantially U-shaped flange which extends around the 90 inturned flange of said first-named guide strip.

FRED MATHEWS.
